DEVICE FOR SHARPENING RAZOR BLADES

James Anderson Morrice, Dowanhill, Glasgow,
ScotlandApplication December 14, 1931, Serial No.
580,964, and in Great Britain December 17,
1930

2 Claims. (Cl. 51—80)

This invention relates to a device for sharpening or stropping razor blades and the like, the device being of the kind comprising an upper roller and a lower roller located within a box having a hinged or removable lid, the upper roller being mounted relatively to the said lid, the said rollers being adapted to operate on both sides of the blade of a safety razor while connected to the razor head or frame.

10 The chief object of the invention is to provide an improved and efficient constructional form of device of the above mentioned character.

According to this invention, there is provided a device of the kind above referred to, wherein 15 the upper and lower rollers are formed with helical grooves adapted to act on both sides of the blade at the edge thereof, such edge when being acted upon lying substantially in alignment with the axes of the rollers, the rollers being provided 20 with gear wheels, a gear wheel or wheels associated with the upper roller being adapted to be brought into engagement with a gear wheel or wheels associated with the bottom roller when the lid of the box is closed.

25 In order that the said invention may be clearly understood and readily carried into effect, the same will now be described more fully, by way of example, with reference to the accompanying drawings, in which:—

30 Figure 1 is a longitudinal vertical sectional view on a slightly enlarged scale, of a device embodying the invention;

Figure 2 is a top plan view corresponding to Figure 1, with the lid of the box opened;

35 Figure 3 is a fragmentary longitudinal sectional view taken approximately on the line 3—3, Figure 2;

Figure 4 is a fragmentary transverse sectional view, on a further enlarged scale, showing the 40 driving clutch and relative connections;

Figure 5 is a sectional side elevation showing a modified form of roller;

Figure 6 is a similar view to Figure 5, showing a further modified form of roller;

45 Figure 7 is a fragmentary longitudinal sectional view thereof;

Figure 8 is a similar view to Figure 7, showing another modified form of roller;

Figures 9 and 10 are also similar views to Figure 7, showing further modified forms of rollers.

Referring first more particularly to Figures 1 to 4 of the drawings, the device comprises a box 1 having hinged or pivotally connected thereto, as at 2, a lid 3, the said box and lid being preferably each moulded from a composition mate-

rial, such, for instance, as that commercially known under the registered trade-mark "bake-lite", or similar material. As shown, in Figures 1 and 2, the end of the lid opposite to that which is hinged or pivoted to the box is provided with 60 an extension or tongue piece 3^a adapted to enter a correspondingly shaped recess 3^b in the box, the said tongue piece secured within the recess by means of spring-pressed balls 3^c carried by the tongue piece and engaging cavities 3^d in the 65 box.

Mounted within the box is a lower roller 4 and mounted within the lid is an upper roller 5, the axes of the said rollers being disposed parallel to the axis of the lid. The said rollers may be rigidly or yieldably mounted, or one roller 70 may be rigidly mounted and the other yieldably mounted, according to requirements, the said rollers being adapted to operate on both sides of the blade 6 of a safety razor 7, indicated by broken lines in Figures 1 and 2, while connected to the razor head or frame. The box 1 is shown formed with integral rests or seatings 8 to locate the razor in position when the blade is being 75 acted upon by the rollers 4 and 5, the lid 3 being 80 also shown provided with integral portions 9 adapted to assist in retaining the razor in position when the lid is closed.

The rollers 4 and 5 may be operated by any 85 suitable gearing, which may be friction gearing, if desired. In the example shown, the said rollers are provided with toothed spur wheels 10 and 11, respectively, adapted to mesh with one another when the lid of the box is closed. The 90 axle of the roller 4 is provided with a toothed pinion 12 operable through an intermediate toothed pinion 13 from a toothed spur wheel 14 secured to a shaft 15 having associated therewith a clutch member 16 adapted to be engaged, under the action of a spring 17, with another 95 clutch member 18 connected, for instance, to the boss of a rotatable crank handle 19 located exteriorly of the box and pivotally jointed, as at 20, so as to permit the handle to be folded in 100 known manner and occupy a position at the side of the box, as indicated by broken lines in Figure 2, when in inoperative position, the crank 21 of the handle then engaging with a hole at the side of the device at the parting between the box and the lid, the hole being formed partly in the box at 22 and partly in the lid at 22', so as to retain the handle in such position, or engaging with a hole in the lid 3 which will act as a catch or a fastener to retain the lid in closed 110 position. The said clutch members 16 and 18

are constructed and arranged in known manner so that the lower roller 4 can be driven only in one direction. The gearing for operating the lower and upper rollers 4 and 5 is arranged relatively to a casing 23 located within the box 1 at one side thereof and is so designed in the example shown that the said rollers are rotated in the desired direction by imparting rotary movement to the handle 19 in clockwise direction.

10 The rollers 4 and 5 are each formed with a single helical groove 24, which may be of right or left hand pitch, as desired, the groove on each roller being of the same hand, as shown, but may be of different hand. Also, if desired, each roller 15 may be formed with helical grooves of right and left hand pitch. The pitch can be determined according to requirements. The rollers, in the example shown, may be made of a relatively hard material, such as metal, or a composition, 20 such, for instance, as "bakelite", as aforesaid, or similar material, the grooves in that event being each provided with a helical strip 25 of leather, rubber, or other compressible material, which may extend entirely, as shown, across the width 25 of the groove, or may extend partially across the groove, and project beyond the periphery of the roller so as to serve normally to effect, for example, the stropping of the blade to be dealt with. When the strip is worn so as to be flush, 30 or approximately flush, with the periphery of the roller, the blade will then be subjected to the action of both the strip and the roller, so that, for example, a combined stropping and sharpening or honing of the blade may be effected.

35 Alternatively, as in the example shown in Figure 5, each of the rollers may be formed of leather, rubber or the like and the helical groove 24 therein may be provided with a strip 26 of metal, glass or any other relatively hard material, 40 which is normally disposed below the periphery of the roller, so that the periphery of the roller may normally effect, for example, the stropping of the blade, but when worn so as to be flush, or approximately flush, with the strip 45 26 of hard material, a combined stropping and sharpening or honing of the blade may be effected.

50

55

60

65

70

75

In a further modification shown in Figures 6 and 7, each roller, preferably made of "bakelite", or similar material, may be provided at the periphery adjacent to one wall of the helical groove 24, with a slightly raised helical portion 27 to act on the edge of the blade being dealt with, so as to remove, for instance, any burr that may be formed at the edge of the blade. If desired, the said wall may be undercut, as shown in Figure 8. In a still further modification, shown in Figure 9, a helical strip 25 of leather or other suitable material, such as aforesaid, may extend partially across the groove 24 in the roller and project slightly beyond the periphery of the raised helical portion 27, or, as shown in Figure 10, may be flush with the periphery of the said raised helical portion.

What I claim is:—

1. A device for sharpening razor blades comprising a box adapted to house a razor having a blade attached thereto, means in said box for supporting the razor, said means including two upright members to cooperate with and support the handle and frame of the razor, a lid hinged to said box and adapted to fold thereon when the device is in operation, a member carried by the lid and formed with a recess to receive and support the guard of the razor, sharpening rolls in both box and lid engaging the razor blade, means for operating said rolls, and means for preventing reverse rotation of said rolls.

2. A device for sharpening razor blades comprising a box adapted to house a razor having a blade attached thereto, a support for said razor and blade to hold the blade in sharpening position and prevent lateral movement of the razor and blade, said support comprising two upright members to cooperate with the handle and frame of the razor, a lid hinged to said box and adapted to fold thereon when the device is in operation, a member carried by the lid and formed with a recess to receive and support the guard of the razor, axles carried by the box and lid, sharpening rolls carried on said axles, means for turning said rolls, and means to limit the rotation of said rolls to one direction.
